UNITED STATES PATENT OFFICE.

HARRIS C. COLEMAN, OF FORT WORTH, TEXAS, ASSIGNOR, BY MESNE ASSIGNMENTS, TO TRAY SERVICE COMPANY, OF DALLAS, TEXAS, A CORPORATION.

DETACHABLE SUPPORTING STAND.

Application filed December 7, 1923. Serial No. 679,186.

This invention relates to a stand adapted for various purposes, which stand is capable of being readily attached to an upright support such as a vertical edge of an automobile 5 door or the like.

In its broad aspect, the invention comprises a supporting stand which may be quickly and readily attached to supporting uprights which vary in thickness within pre-10 determined limits. The invention is especially adaptable to supporting stands for dispensing trays for soda water fountains, which stands are so constructed as to be detachably supported on the upper edge of 15 the door of an automobile or the like.

The minor details of the invention comprise the construction of the stand so that it is adapted to support trays of different dimensions; to clamp such trays in position on the stand, and to provide means for clamping the stand itself to trays of different thickness, and in addition, to construct such clamping means so that it will fold compactly into the supporting surface when 25 the stand is not in use.

Other features of the invention will be apparent from a perusal of the following specification, wherein—

Figure 1 is a perspective view of the de-30 vice with the tray clamped in serving position;

Fig. 2 is an enlarged side view;

Fig. 3 is a view of the detached support in folded position, and

Fig. 4 is an end view of one-half of the support.

Referring now to the drawings in detail, the stand comprises a substantially flat supporting surface which, in the broad aspect 40 of the invention, may be a plain flat surface for any desired utility.

In the specific embodiment shown, the device is illustrated as a serving tray, for dispensing fountains. At the present time 45 there is a great demand for a suitable serving tray for serving automobilists with fountain drinks and beverages. These fountain drinks are generally carried out to the automobilists by the dispensers on trays, and 50 no proper means has been heretofore provided for supporting these trays in the automobile while the beverages are being drunk.

In the specific embodiment of the invention, the stand comprises three parallel 55 strips of metal 1, 2 and 3 rigidly united by

transverse strips 4 and 5, suitably joined to the parallel strips as by soldering, spot welding or by rivets. At one end, each one of the outer strips is provided with a curled up portion 6 to provide a stationary clamping jaw. The respective clamping jaws of these outer strips are arranged at one end of the stand and in the same plane. The intermediate parallel strip 2 is formed as a channel beam so as to provide an inner 60 guideway in which telescopingly slides a clamping member 7 having an upwardly curled end 8 opposed to the curled portions of the outer strips 1 and 3. The under side of the clamping strip 7 is provided with a suitable stop in order to limit the outward movement of this member in the channel strip 2. By means of this construction, the intermediate clamp can be moved toward 65 and from the clamping jaw 6 so as to accommodate trays of different size.

Means is provided for attaching the stand to any convenient upright support. The most practical support is the side door of the automobile. The stand is adapted to 70 be slipped over the side door and to be supported therefrom so as to hold the tray on the stand in substantially horizontal position. A simple form of fastening means is shown as comprising two depending feet or 75 fingers 9 and 10, each one of which is fastened preferably to the end of an outer strip. In its particular form, each foot comprises a sheet metal strip having the ears 11 thereof bent upwardly to form bearings for 80 a pivot pin 12 passing through a lug or a hole 13 in the outer strip. The foot being thus pivoted to the strip, the end thereof nearest the pivotal point will contact with the curved up-turned portion to limit the 85 upward swing of the foot away from the under surface of the strip and thus hold the foot in a definite depending position.

As illustrated, this construction and pivotal mounting of the foot permits it to swing 90 upwardly into a position parallel or substantially parallel with the flat outer strip. 95 Cooperating with these two outer feet is an intermediate foot 14 which is adjustably supported on the intermediate strip 2 so that 100 when moved away from the depending pair of feet 9, the stand can be slipped over the edge of the upstanding door and the intermediate foot moved along the intermediate strip to firmly clamp the stand against the 105

edge of the upstanding door and the intermediate foot moved along the intermediate strip to firmly clamp the stand against the 110

door in horizontal position. This intermediate foot is constructed like the feet 9 and 10, except that it is considerably longer. It is provided with folded ears 15, which at 5 the end, are provided with a pivot pin 16 which passes over the intermediate channel strip 2, thereby locking the intermediate foot 14 loosely on the intermediate strip. In other words, the pivot pin 16 and the 10 end 17 of the foot form a guideway through which the intermediate strip 2 passes, and this end 17, in connection with the pivot pin limits the downward depending movement of this intermediate foot, while at the 15 same time, permits it to slide along freely on the intermediate strip. In addition, this construction enables the intermediate foot to be folded upwardly into flat contacting position against the under side of the intermediate strip, so that when the stand is not 20 in use, it will lie flat, the intermediate foot and two outer feet folding up flat against the under surface of the outer and intermediate strips. This facilitates compact 25 packing and storage of these devices.

The under surfaces of the strips are preferably provided with lugs 18, 19, 20 and 21, upon which the stand may rest, so that all strain is removed from the folded feet by 30 the weight of the stand resting on these lugs. These lugs may be provided with rubber surfaces to prevent scratching, and in addition thereto, the feet may be provided with rubber facings to prevent them 35 scratching or marring the door or other supporting surface.

It is obvious that minor changes in the details of construction and the arrangement of the parts may be made without departing from the spirit of the invention as set 40 forth in the appended claims.

Having thus described the invention, what I claim as new and desire to secure by Letters Patent, is—

45 1. A serving tray for automobiles and the like comprising two interconnected substantially parallel supports, each having a corresponding end curled upwardly to form one member of a tray clamp, an intermediate 50 support having its end curled in opposition to the first-mentioned curled ends to form the supplementary tray clamping member, a pair of feet, each being pivoted to and depending from the end of each support and 55 arranged to fold substantially flat to the underside of said support, and a central foot hingedly connected to said intermediate member and depending downwardly in spaced relation to said pair of feet whereby 60 to receive therebetween the upstanding edge of an automobile door or other support, said central foot also being arranged to fold substantially flat to the underside of said support.

2. A serving tray for automobiles and the

like comprising three parallel supports forming a tray support, means to attach said supports to the free upper edge of an automobile door or the like, the outer supports having their corresponding ends curled 70 upwardly to form a tray clamping means, the intermediate support being in the form of a channel member, a tray clamping member having an end curled up in opposition to the curled ends of the outer supports, said 75 member telescoping within said channel member to permit the adjustment of said curled end relatively to the curled ends of said outer members.

3. A serving tray for automobiles and the like comprising a substantially flat support, relatively short lugs or feet depending from the under surface of said support upon which said support is adapted to rest on a flat surface, a plurality of depending fingers connected to said support and adapted to receive and clamp therebetween the upper vertical edge of the automobile door or the like whereby to hold said flat support in a substantial horizontal position, and means 80 for permitting said fingers to be folded substantially flat to the under surface of said support and within the plane of the bottom ends of said feet when not intended for use 85 whereby said flat support can rest upon said lugs.

4. A device of the character described comprising a support, a plurality of fingers, means forming a pivotal connection between each finger and said support to permit said fingers to depend therefrom, said means having a portion adapted to abut said support to clamp the fingers in desired position and being constructed and arranged to permit said fingers to fold snugly to the underside of said support, at least one of said means forming a freely slideable connection with said support whereby to permit the corresponding finger to be clamped in any slideable position of adjustment.

5. A device of the class described comprising a support, a plurality of fingers adapted to grip an upright to maintain said support in horizontal position, means pivotally connecting said fingers to said support, said pivotal connection permitting said fingers to swing freely in one direction to fold snugly against the underside of said support and said pivotal connection being constructed and arranged to prevent the fingers from swinging beyond a predetermined arc in the reverse direction, one of said pivotal connections being shiftable relatively to the remainder to permit the clamping adjustment of said fingers.

6. A serving tray for automobiles and the like comprising members forming a supporting platform, a plurality of fingers adapted clampingly to engage an upright, the fingers having spaced ears at their upper ends and

a pivotal pin passing therethrough to engage said members and form a pivotal connection between the finger and a member, the upper end of each finger between said ears forming an abutment to contact the member and prevent swinging movement of said finger beyond a predetermined arc.

7. A serving tray for automobiles and the like comprising members forming a supporting platform, a plurality of fingers adapted clampingly to engage an upright, each finger having spaced ears at its upper end and a pivotal pin passing therethrough to engage a member whereby to form a pivotal connection, the upper end of each finger between said ears forming an abutment to engage the underside of the member to prevent swinging movement of the finger in one direction beyond a predetermined arc, at least one of the fingers having its pivotal

pin disposed over said member and freely slideable therealong to permit the clamping adjustment of said finger.

8. A serving tray for automobiles and the like comprising three parallel interconnected metal strips forming a flat support, each of said strips having an outer end formed with an upturned portion to engage the side of a tray, means permitting one of said strips to shift endwise relatively to the others to adjust the distance between said upturned ends, a plurality of sheet metal fingers having their upper ends folded to provide spaced ears and an intermediate abutment at the end of the finger between said ears, each finger having a pivotal pin passing through said ears and engaging a metal strip.

In testimony whereof, I affix my signature.
HARRIS C. COLEMAN.
